UNITED STATES PATENT OFFICE.

FRANÇOIS BAVEREY, OF LYON, FRANCE, ASSIGNOR TO SOCIÉTÉ DU CARBURATEUR ZENITH, OF LYON, FRANCE, A CORPORATION OF FRANCE.

CARBURETER.

1,099,277.

Specification of Letters Patent.

Patented June 9, 1914.

Application filed February 24, 1913. Serial No. 750,250.

To all whom it may concern:

Be it known that I, FRANÇOIS BAVEREY, citizen of the French Republic, residing at Lyon, Department of the Rhône, in France, have invented certain new and useful Improvements in Carbureters; and I do hereby declare the following to be a full, clear, and exact description of the invention, such as will enable others skilled in the art to which it appertains to make and use the same.

This invention relates to improvements in and relating to internal combustion engines of the kind having two carbureters one for heavy fuel and the other for light fuel. According to the present invention the two carbureters operate automatically by means of a compensating outlet controlled by the operation of the engine so as to supply the latter with light fuel during slow running and a diminishing proportion of light fuel and an increasing proportion of heavy fuel as the speed of the engine increases. This result is obtained by the combination of two carbureters, one of ordinary construction adapted to furnish for each cylinder charge a larger quantity of heavy fuel in proportion as the suction increases; the other carbureter is of the type illustrated in my prior Patent, No. 907,953, issued December 29, 1908, and commonly known as the Zenith type and furnishes a constant quantity of light fuel in a unit of time, so that the quantity of light fuel supplied will be smaller in proportion as the number of strokes of the engine is greater. Accordingly, an engine thus constructed automatically substitutes to an increasing extent, in proportion as the engine consumes more fuel, a heavy and economical oil for a light and costly fuel. The economy thus obtained is particularly important for the well defined class of carbureters to which the invention is applicable.

The invention is illustrated in the accompanying drawing which represents a carbureter of the well-known "Zenith" type to which the invention has been applied.

The carbureter shown in the drawing comprises two jets supplied with two different liquids. From a constant level reservoir 1, the inner jet 3 of the injector 14 is supplied in the ordinary conditions through the pipe 2. This jet opens to the center of the suction conduit 4 beneath the throttling elements 5; air is supplied to the conduit 4 through an opening 6. The stronger the suc-

tion, the more fuel is supplied by the inner jet 3, that is to say, in proportion as the speed of the engine is greater. In accordance with the invention it is this jet that is supplied with heavy cheap fuel and the reservoir 1 is therefore charged with such fuel. A second reservoir 7, charged with light fuel supplies a conduit 9 open to the atmosphere. This pipe supplies two jets, one of which operates constantly and the other intermittently.

A pipe 8 enters the conduit 9 and opens into the suction conduit 4 in proximity to the edge of the throttle valve 5. The conduit 9 also communicates through the conduit 12, with the outer annular jet 13 of the injector 14. The conduit 9 draws from the reservoir 7 a quantity of fuel which does not increase with the speed of the engine, i. e., the carbureter supplies a constant quantity of fuel in a unit of time. When the valve 5 is open and the engine running, this constant quantity of fuel is in a diminishing ratio for each cylinder charge in proportion as the speed increases, while the jet 3, on the contrary furnishes for each cylinder charge a larger quantity of fuel in proportion as the suction increases. This distribution is produced automatically by the engine according to its speed. As its total consumption increases, it consumes so much the more heavy fuel and so much the less light fuel. The pipe 8 which does not descend to the bottom of the pipe 9, acts only on starting and at low speeds.

What I claim is:

1. A carbureter for internal combustion engines, comprising an air conduit, a reservoir for heavy fuel, means to supply said heavy fuel to the air conduit in quantities increasing with the speed of the engine, a light fuel reservoir, and means to deliver during normal running a constant quantity of the light fuel to the air conduit in a given period of time.

2. A carbureter for internal combustion engines, comprising an air conduit, a reservoir for heavy fuel, a delivery nozzle adapted to supply fuel to the air conduit in quantities increasing with the speed of the engine, a light fuel reservoir, and means to deliver during normal running a constant quantity of the light fuel to the air conduit in a given period of time so that as the speed of the engine increases the proportion of

light fuel in each charge becomes less and the proportion of heavy fuel becomes greater.

3. In a carburetor for internal combustion engines, the combination of means to supply a quantity of heavy fuel increasing with the speed of the engine, and means to supply during normal running a constant quantity of light fuel independently of the speed of 10 the engine whereby the proportion of heavy

fuel in each charge becomes greater as the speed increases and the proportion of light fuel becomes less.

In testimony whereof I affix my signature, in presence of two witnesses.

FRANÇOIS BAVEREY.
